UNITED STATES PATENT OFFICE.

HARVEY F. MARANVILLE, OF AKRON, OHIO.

NEST.

1,320,774.

Specification of Letters Patent.

Patented Nov. 4, 1919.

Application filed February 5, 1916. Serial No. 76,240.

To all whom it may concern:

Be it known that I, HARVEY F. MARANVILLE, a citizen of the United States, residing at Akron, in the county of Summit and State of Ohio, have invented a certain new and useful Improvement in Nests, of which the following is a full, clear, and exact description, reference being had to the accompanying drawings.

10 This invention relates to nests for birds, particularly for hens' nests of the design to trap eggs therein for purposes of identification. Previous devices of this nature have frequently been crude in construction and 15 have depended upon a swinging door which had to be pushed open against the inclination of the fowl, frequently frightening it and rendering it averse to the use of those nests. The object of this invention is to remedy 20 this defect, and also to provide a sanitary nest, with improved devices for catching the eggs and allowing the escape of droppings. In the drawing, Figure 1 is a perspective view of a set of the improved nests showing 25 the drop or shutter closed in some instances and open in others; Fig. 2 is a vertical section of a nest with the shutter open; Fig. 3 is a horizontal sectional view of the nest on the line 3—3 of Fig. 2; Figs. 4 and 30 5 vertical and horizontal sectional views of the nest on the lines 4—4 and 5—5 of Fig. 2. Figs. 6 and 7 are details in section and perspective of supports for the nest bottom.

35 This preferred construction of improved nest consists of an open rectangular cabinet 1 having one side open as at 2 and having upon said open side a drawer 3 for the reception of the eggs. Mounted above the 40 drawer is a substantially horizontal tray 4, preferably of metal although wood is sufficient, the same being supported upon pivots 5 so as to tend to rock forward. The pivots 5 comprise lugs struck in from channelled plates 50 secured to the sides of the casing. The bottom of the tray slopes downwardly 45 from the sides to a central opening 6 disposed over the said drawer.

Inside the open part of said casing, above 50 said tray is a curved shutter 10 made preferably in the form of a segment of a cylinder and having at each end a radial arm 11 pivoted upon a suitable stud 12 projecting from the side of the casing substantially concen-

tric with such cylindrical surface. The rear- 55 ward part of said shutter is bent downwardly as shown at 13 so as to be engaged by a catch 14 carried at the upper end of a movable rod 15 which is also connected to the tray 4. The studs 12 are located at the rear 60 of the center of gravity of the shutter so as to cause the shutter to fall by its own weight upon the release of the catch, and the tray is likewise pivoted at the rear of its center 65 of gravity so as to cause it to remain normally in forwardly inclined position with such catch in engagement, but to become rocked in the opposite direction by the weight of a fowl. The front of the shutter is preferably cut away for a short distance as 70 shown at 16 to afford a small amount of air and light to the interior and also to permit the attendant to learn the presence of the bird therein. The eggs fall through the opening 6 into the drawer 3 which is cushioned 75 with a spun wire receiver 17 or the like to prevent breakage.

In order that the fowl may have a comfortable and sanitary nest, I preferably employ a cover for the tray 4 although the same 80 is not limited to use with nests of this nature. Said cover consists of a rectangular wire frame work 20 resting in the tray and having loosely affixed thereto a cloth covering 21, the center whereof is formed with the 85 opening 22. The cloth is of a heavy nature and a close weave so as to resist destruction by the birds, and is soaked in a suitable disinfectant or vermin-repelling material so as not only to prevent the nest from becoming 90 infested, but also to drive away any which the fowl may bring. Said cover is preferably reversible to permit longer use before cleaning.

The receiver 17 is of peculiar construction, 95 and is adapted to catch the eggs while permitting the droppings to fall through the same. The receiver is preferably made of woven wire and is a concave annulus around a central opening 30, the edge of the receiver 100 around said opening being curved downwardly as shown to provide a blunt or rounded edge. In the central opening 30 is an ovoid cushion or member 32, preferably made of woven wire and projecting at its 105 upper end above the plane of the margin of the opening 30. This cushion is mounted in a small circular base ring 33 supported

by cross wires 34 which extend across the bottom of the drawer 3 above an opening 35 in the bottom of said drawer.

When a fowl enters the nest and turns around therein as fowls are accustomed to do, its weight rocks the rear end of the tray downwardly and releases the latch 14, and the shutter 10 drops by gravity and traps the fowl in the nest. When an egg is laid, it falls through the openings 22 and 6 and striking on the cushion 32 is deflected, rolls into the receiver 17, the space between the cushion and the margin of the opening being too small for an egg to drop through said opening. The droppings of the fowl, however, will fall upon said cushion and down through the openings 30 and 35 to the ground or floor below the nests. Or any particles caught on the cushion device may be washed off or easily dislodged upon removal of the drawer.

It may be noted that the flanges 51 of the side pieces 50 project into the line of movement of the tray 6, which by contact therewith is prevented from rocking beyond the distance necessary to engage or disengage the latch 14 with the lip 13. Said latch is

also inclined toward the front of the shutter, so that when the shutter is lifted to reset the same the latch will engage automatically.

This invention is not limited to the exact structure shown, but may be embodied in various structures within the scope of the following claims.

Having thus described my invention, what I claim is:—

1. In a nest, a bottom having an opening, and an egg receiver thereunder, said egg receiver having an opening with a raised rim around the same, and an inclined cushion projecting above said rim, to guide eggs into the receiver, and being spaced from said rim to allow the fall of droppings through the last mentioned opening.

2. A nest having a bottom with an opening therein, a removable frame upon said bottom, and a fabric cover extending across said frame and having an opening registering with said opening, said cover being normally spaced above said bottom.

In testimony whereof, I hereunto affix my signature.

HARVEY F. MARANVILLE.
